UNITED STATES PATENT OFFICE.

HARRY S. PIERCE, OF WILMINGTON, DELAWARE.

SASH ATTACHMENT.

1,349,168.

Specification of Letters Patent. Patented Aug. 10, 1920.

Application filed August 22, 1919. Serial No. 319,160.

To all whom it may concern:

Be it known that I, HARRY S. PIERCE, a citizen of the United States, residing at Wilmington, in the county of New Castle and

5 State of Delaware, have invented new and useful Improvements in Sash Attachments, of which the following is a specification.

This invention relates to improvements in window sashes and particularly to means 10 for holding the sash in adjusted position by the use of the usual sash weights or cords.

More specifically stated, the invention aims to provide an attachment carried by 15 the sash and including spring pressed rollers engageable with the window frame for yieldingly holding the sash in position, yet permitting it to be easily raised or lowered.

Another object is the provision of means 20 for regulating the pressure of the rollers upon the window frame, so as to take up wear and prevent the sash from rattling in windy weather and to permit of the removal of the sash, when desired.

Other objects and advantages of the invention will appear as the following description is read in connection with the accompanying drawings.

In the drawings:

Figure 1 is a view in elevation showing 30 a fragmentary portion of a window frame with the sash therein and the invention applied thereto.

Fig. 2 is an enlarged sectional view on the line 2—2 of Fig. 1.

35 Fig. 3 is an enlarged plan view of one end of the top rail of the sash showing the application of the invention.

Fig. 4 is an edge view of the same.

Fig. 5 is a sectional view on the line 5—5 40 of Fig. 4.

Fig. 6 is a detail perspective view of the pivoted backing arm.

Fig. 7 is a like view of the sliding frame and roller.

45 Referring in detail to the drawings, like characters of reference denote corresponding parts throughout the several views.

In the use of the invention, there is provided a casing 10, having at one end an extension 11, for the passage of a screw 12, or other fastening device, by means of which this end of the casing is secured within a socket formed in the corner of the sash.

50 The opposite end of the casing is provided with a plate 13, having an opening therein 55 for the passage of a screw 14, which aids

in securing the device in position. Side plates 15 form a part of the casing, being secured in position through the medium of screws 16.

One of the devices is located at each corner of the sash, as shown in Fig. 1 of the drawings, the casings being mortised within the sash, so that their edges are flush with the top and bottom rails and stiles. Each 60 of the casings has positioned therein a sliding frame 18, the latter having pivotally mounted therein, as shown at 19, a roller 20, the said roller projecting through an opening 21 in the plate 13, so as to contact 65 with the sides of the window frame, the said rollers riding in the grooves provided for the travel of the sash.

Pivotally mounted within the casing 10, as indicated at 22, is an arm 23, the latter 70 being of curved formation and having one end provided with an opening 24, for the reception of a set screw 25, the latter being adapted to threadedly engage a socket 26 in the extension 11 of the casing. The opposite end of the arm 23 is provided with a cross bar or head 27, to which is secured a spring 28. This spring is preferably of 75 curved formation and is adapted to bear against the frame 18 for the purpose of yieldingly forcing the roller 20 against the window frame. The contact of the roller with the window frame may be regulated by adjusting the screw 25. For example, by 80 loosening the screw, the arm 23 may be allowed to move upon its pivot, so that the roller 20 may move inward with the frame 18 a distance limited by the adjustment of the screw. By loosening or removing the 85 screws 25, the sash may be easily removed 90 or inserted within the window frame.

It will be seen by reference to the accompanying drawings and the foregoing description, that the invention provides simple and efficient means for holding a window 100 sash in adjusted position, said means being capable of adjustment to regulate the contact of the rollers with the sash.

The invention is susceptible of various changes in its form, proportions and minor 105 details of construction and the right is herein reserved to make such changes as properly fall within the scope of the appended claim.

Having described the invention, what is 110 claimed is:

A sash attachment comprising a casing

open at one end and having a slot in the side wall of the casing, a frame slidable in said casing, a roller journaled in the frame and extending through the opening in the 5 end of the casing, an arm pivotally mounted within the casing, a spring located at one end of the arm and engageable with the sliding frame for yieldingly holding the

roller against the window frame, an offset terminal portion at the opposite end of the 10 frame, whereby the latter will extend into the slot of the side wall of the casing and means for adjustably securing the terminal portion of the arm to the casing.

In testimony whereof I affix my signature. 15
HARRY S. PIERCE.
